UNITED STATES PATENT OFFICE.

HARRY A. MUSSER, OF LEXINGTON, KENTUCKY, ASSIGNOR OF ONE-HALF TO W. O. WALKER, OF OIL CITY, PENNSYLVANIA.

GAS-BURNER.

1,359,417.

Specification of Letters Patent. Patented Nov. 16, 1920.

Application filed February 28, 1919. Serial No. 279,714.

To all whom it may concern:

Be it known that I, HARRY A. MUSSER, a citizen of the United States, residing at Lexington, in the county of Fayette and 5 State of Kentucky, have invented new and useful Improvements in Gas-Burners, of which the following is a specification.

This invention comprehends generally improvements in that class of inventions 10 known as oil and gas burners and more particularly relates to a combination gas burner.

The invention has for its principal object to provide a device of the above mentioned character designed so that an effective gas 15 flame will be produced at all times regardless of the pressure of the gas the parts being related so that when the gas is at a normal or standard pressure the air mixer may be employed whereas when the low pressure 20 exists the valves may be adjusted to assure of the mixing of the air and gas at the point of combustion.

It is an additional object of this invention to provide a device of the above mentioned 25 character composed of main and auxiliary burners designed to be used respectively when the gas is at a normal or a standard pressure and at a low pressure, valves acting in conjunction therewith for controlling the 30 flow of gas to the desired burner.

It is a more specific object of this invention to provide a device of the above mentioned character wherein means is employed for covering the secondary or low pressure 35 burner when the same is not in use.

It is an additional object of this invention to provide a device of the above mentioned character which is simple in construction, thoroughly reliable and efficient in its purpose and inexpensive in manufacture. 40

Other objects will be in part obvious and in part hereinafter set forth.

The invention accordingly consists in the features of construction, the combination of 45 elements and the arrangement of parts which will be amplified in the construction hereinafter described and the scope of the application of which will be indicated in the appended claims.

50 The invention is clearly illustrated in the accompanying drawings, in which—

Figure 1 is a top plan view of one form of the invention.

Fig. 2 is a side elevation thereof.

Fig. 3 is a top plan view of the flame 55 evener.

Fig. 4 is a perspective detail of the cover for the auxiliary or low pressure burner.

Fig. 5 is the perspective side elevation of another form of the invention. 60

Fig. 6 is a top plan view thereof.

Fig. 7 is a cross-sectional view taken on the line 7—7 of Fig. 5, and

Fig. 8 is a perspective detail of the cover for the auxiliary burner. 65

Fig. 9 is a perspective detail view showing the flame evener and deflector.

Similar characters of reference are employed in all of the above described views, to indicate corresponding parts. 70

Referring now, more particularly, to the accompanying drawings, there is illustrated a main supply pipe 1 from which extends a branch pipe 2, the flow of gas through which is controlled by a manually adjustable valve 3, interposed therein. The pipe 2 terminates in a jet 4 and this jet is disposed within a mixer 5 formed desirably by flaring the adjacent end of the tubular stem 6 of the main burner 7, the latter being desirably of round configuration and formed with a plurality of perforations 8 which serve as gas outlets. When the pressure is normal the valve 3 is open and the burner 7 lighted. 75

As intimated, means have been provided for procuring the effective burning of the gas when the pressure is low. In reducing this feature of the invention to practice another conducting pipe 9 depends from the branch at a point between the valve and the main supply pipe 1 and has mounted therein a valve 10, manually operable for controlling the flow of gas therethrough. The pipe 9 is joined with the tubular stem 11 of the auxiliary burner generally designated by 80

the numeral 12. Like the main burner 7 the auxiliary burner is round but considerably smaller and is disposed concentrically beneath the main burner the upper surface thereof being formed with gas outlet openings 13. An upright bracket 14 is carried by the stem 11 and has its upper end bifurcated as at 15, for raising and supporting the stem of the main burner. By this arrangement, when the gas is at a low pressure the valve 3 is closed and the valve 10 opened to permit of the lighting of the burner 12. In this connection it is to be ob- 85

served particularly that owing to the low pressure the mixture of the gas with the air occurs at the point of combustion.

The improved flame evener, generally designated by the numeral 16, consists of a disk-like body 17, from the outer periphery of which radiated arms 18 will be joined and reinforced by an outer rim or link 19. In use, the arms are disposed on the upper surface of the main burner 7 so as to position the body 17 directly above the auxiliary burner 12 so that the flames which arise therefrom will be equally distributed on the vessel (not shown) adapted to be disposed above the main burner.

In order to protect the auxiliary burner when the main burner is in use a cylindrical cap or cover 20 is employed and is designed for engagement with the auxiliary burner as indicated in Fig. 4.

In Figs. 5 to 8 there is illustrated another form of the invention which is particularly adapted for use in heating ovens of stoves or ranges and oblong or oval heating stoves. In reducing this form of the invention to practice the main burner indicated generally by the numeral 21 instead of being round is desirably relatively long and narrow being formed with a stem 22 which is connected with the main supply in a manner similar as in the preferred form. The upper side edges of the burner 21 are inclined as at 23 and provided with gas outlets 24 while projecting from opposite sides of this burner are opposed and outwardly extending flame evening and deflecting wings or blades 25. As in the preferred form the main burner is supported by a bracket 26 which is carried by the auxiliary burner indicated generally by the numeral 27 disposed beneath the main burner. This auxiliary burner is connected with the source of supply in a similar manner as shown in the preferred form while the shape of the burner instead of being round is forked and consists of an intermediate portion 28 and spaced side arms 29 the upper surfaces of which are formed with gas outlet openings 30. The flames which issue from the auxiliary burner 27 are deflected by the wings or blades 25 so as to be equally distributed on the under surface of the vessel (not shown), adapted to be disposed above the main burner.

As in the other form, suitable means have been provided for protecting the auxiliary burner 27, in the present instance consisting

of a substantially rectangular cover plate 31 formed with depending flanges 32, one end of the flange of which is provided with a recess 33 with straddled engagement about the stem of the auxiliary burner 27.

What I claim is:

1. The combination with a main gas burner having a mixer and control valve and an auxiliary burner disposed below the main burner and provided with a controlling valve, and a flame evener removably supported by the main burner for operative connection with the flame from the auxiliary burner.

2. The combination with the main gas burner, a mixer therefor and a valve for controlling the flow of gas to the burner, of an auxiliary burner disposed beneath the main burner, a valve for controlling the flow of gas to the auxiliary burner, a flame evener disposed above the auxiliary burner and supported by the main burner, and a cover for removably covering the auxiliary burner when not in use.

3. The combination with a main gas burner, having a mixer and controlling valve, of an auxiliary burner positioned below the main burner and provided with a controlling valve, and a flame evener and a cover for alternate use with the auxiliary burner.

4. A device of the character described including in combination with a gas supply pipe a branch pipe leading therefrom and terminating at its opposite end with a jet, a valve for controlling the flow of gas through the branch pipe, a main burner, a tubular stem projecting therefrom, a mixer formed at the terminal of the stem and disposed about the jet, a conducting pipe leading from the branch pipe, a valve for controlling the flow of gas therethrough, an auxiliary burner disposed concentrically beneath the main burner, a stem projecting therefrom and joined with the last mentioned pipe, a bracket carried by the stem of the auxiliary burner for supporting the main burner, a flame deflector mounted on the main burner for acting on the flames from the auxiliary burner when the main burner is not in use, and a cover adapted to be connected to the auxiliary burner when not in use.

In testimony whereof I affix my signature.

HARRY A. MUSSER.
